UNITED STATES PATENT OFFICE.

JAMES M. BURTON, OF LONG ISLAND CITY, NEW YORK, ASSIGNOR TO NEPTUNE METER COMPANY, OF NEW YORK, N. Y., A CORPORATION OF NEW JERSEY.

WATER-METER.

1,097,212.

Specification of Letters Patent. Patented May 19, 1914.

Original application filed December 15, 1911, Serial No. 665,924. Divided and this application filed August 28, 1913. Serial No. 787,076.

To all whom it may concern:

Be it known that I, JAMES M. BURTON, a citizen of the United States, residing in Long Island City, Queens county, State of New York, have invented certain new and useful Improvements in Water-Meters, of which the following is a specification, reference being had to the accompanying drawings, which form a part hereof.

10 In a co-pending application filed December 15, 1911, Serial No. 665,924, of which this case is a division, there is shown and described a water meter which comprises a casting with a high-duty straight-flow unobstructed passage from inlet to outlet and a low-duty passage from inlet to outlet, a proportional metering device for high-duty flow at one side of the path of straight-flow and a separate metering device for low-duty flow.

20 The present invention has for its object to provide improved valves to control the high-duty passage and the low-duty passage of the meters of the general type referred to above, constructed and coöperating so that one valve is closed as the other opens, the closure of the low-duty valve taking place when the change from low-duty conditions to high-duty conditions occurs, before the high-duty valve, actuated by the increase in 30 the pressure differential, has moved sufficiently to permit the escape of water past it.

In accordance with the invention, the opening movement of the high-duty valve is preferably caused, through suitable mechanical connections, to close the low-duty valve and the invention consists in part in the devices whereby such relative movement of the valves is effected.

Reference is now to be had to the accompanying drawings for a detailed description of the invention in which—

Figure 1 is a view in longitudinal, vertical section of a meter which embodies the invention, the connections whereby the low-duty valve is closed by the opening movement of the high-duty valve being shown in elevation. Fig. 2 is a view in section on the planes indicated by the broken line 2—2 of Fig. 1. Fig. 3 is a view similar to Fig. 1 but showing the high-duty passage open and the valves and their connections in the positions which they assume under such conditions. Fig. 4 is a detail view showing the valves and their connections. Fig. 5 is a de-

tail view illustrating an adjusting device employed in the connections between the valves, the scale being larger than that of the other figures. Fig. 6 is a detail view in section on the plane indicated by the broken line 6—6 of Fig. 5.

For a clear understanding of the mode of operation of the improved valves and the valve connections it is believed that a general description of the metering devices proper will be conducive to a clearer understanding thereof. The casing *a*, having an inlet *b* and an outlet *c* is shown as having a transverse wall *a'* which is provided with a high-duty orifice *a²* in a straight line with the inlet and the outlet and of substantially the same area, and with a low-duty orifice *a³* at one side of the straight-flow path, the wall *a'* forming on one side an inlet chamber *a⁴* and on the other side a discharge chamber *a⁵*. An intermediate chamber *a⁶* is formed by a wall *a⁷* which has an inlet nozzle *a⁸* in a line with the inlet *b* and the outlet *c*, and an orifice or orifices *a⁹* at one side of the path of straight-flow, for the turbine wheel or wheels *a¹⁰* from which the high-duty register, indicated at *a¹¹*, is driven by a shaft *a¹²* in the usual manner. The low-duty metering device indicated at *a¹³*, may also be of any usual or suitable form, being shown as of the displacement or disk type, and as inclosed in 80 a casing *a¹⁴* in front of the orifice *a³*. It will be observed that the inlet chamber *a⁴* forms a high-duty straight-flow passage from the inlet *b* to the intermediate chamber *a⁶*, a proportional-flow passage from the inlet to the 90 proportional metering device, and a low-duty flow passage from the inlet to the discharge chamber *a⁵* through the wheels of the low-duty metering device *a¹³*. When the high-duty straight-flow passage is closed by 95 its valve, as hereinafter described, the entire volume of water, under low-duty conditions, that is, under a low pressure differential, passes through the low-duty metering device and is measured thereby. On the other hand, 100 when the high-duty, straight-flow passage is open and the low-duty passage is closed, the inlet chamber *a⁴* is filled completely by the water (the entrapped air being permitted to escape, as usual), and thereafter a certain 105 definite proportion of the entire volume passes through the proportional metering device and actuates the same so that the en-

tire flow under high-duty conditions, that is, under a high pressure differential, is measured proportionally.

In the orifice a^2 of the wall a' is preferably secured a sleeve d which forms a seat for the high-duty valve, and in the low-duty orifice a^3 is preferably secured a sleeve e which supports the low-duty valve. The high-duty valve f comprises a main part f' , a part f^2 which is movable relatively to the main part and in the same direction and, preferably, a flexible diaphragm f^3 which overlies the main part f' and the relatively movable part f^2 and is pressed by the main part f' against the valve seat d . In the construction shown, the face of the main part f' is recessed, as at f^4 , to receive the relatively movable part f^2 and the stem f^5 of the latter is projected rearwardly through the main part f' and is pivotally and loosely connected to two toggle levers f^6 which are pivoted as at f^7 on the main part f' . A yoke f^8 is pivotally connected at its ends to toggle levers f^6 between their pivot points f^7 and the stem f^5 and is itself pivoted upon an arm or arms g mounted on a shaft g' which is supported in suitable bearings in bracket arms g^2 secured to the wall a' . An arm g^3 (shown in dotted lines in Figs. 1 and 3) fixed on the shaft g' , carries a roller g^4 which bears against a cam arm h . The latter is pivoted as at h' and has suspended therefrom a weight h^2 . By these means the high-duty valve f is held to its seat against the low pressure differential, but when the pressure differential rises above the predetermined degree and the valve f is opened, the roller g^4 acts against the underside of the cam lever h to swing the same on its pivot, against the resistance of the weight h^2 , and as the arm g^3 rises the cam arm is swung back to carry the weight h^2 toward the vertical plane of the axis of the cam arm, whereby the resistance offered by the weight to the opening of the valve is reduced and the valve offers practically no resistance to the passage of the water under it, the valve being raised meanwhile to a position above the path of straight-flow. The low-duty valve is closed during the initial movement of the part f^2 of the high-duty valve and is thereafter held closed by means now to be described. To the shaft g' is secured an arm i and loosely mounted on the shaft, adjacent to the arm i , is a cam plate or quadrant k which is adjustable with respect to the arm i by means of an eccentric screw i' carried by the quadrant k and entering the slot i^2 in the arm i , so that by a slight rotation of the screw i' the relative position of the arm and quadrant can be changed. The two parts may then be secured in adjusted position by a clamping screw i^3 . The cam plate or quadrant k is formed with a cam path or groove, the

greater portion k' of which is concentric with the shaft g' while a jog or offset k^2 is formed at one end. This cam path is entered by a projection l' on a lever l , close to the pivot l' thereof, so that when the quadrant k starts to move from the position indicated in Fig. 1, to the position indicated in Fig. 4, the lever l , which may be counterbalanced as at l^3 , is tilted quickly on its axis. The free end of the lever is connected by a link l^4 with an arm m' on the shaft m^2 of the low-duty valve m which is pivotally mounted in the sleeve e . The initial movement of the quadrant k and the consequent closing of the valve m are effected before the high-duty valve f leaves its seat by the relative movement of the part f^2 of the valve, for as the pressure differential rises above the predetermined degree the excess of pressure on the diaphragm f^3 presses the latter toward the outlet and so moves the part f^2 with respect to the main part f' of the valve. This movement of the part f^2 moves the toggle levers f^6 on their pivots and, through the yoke f^8 , arm g , shaft g' and arm i , imparts to the quadrant k that degree of motion which is necessary to effect the movement of the valve lever l to close the valve m before the diaphragm f^3 is moved from its seat against the sleeve d . As the low-duty valve is closed and the entire pressure differential is exerted against the diaphragm f^3 the whole valve f then moves away from the valve seat and into the position represented in Fig. 3. The positions which the parts assume at the initial movement of the part f^2 of the valve are clearly shown in Fig. 4.

It will be understood without further explanation that the entire flow, under low-duty conditions, is measured by the low-duty measuring device a^{13} , the high-duty valve being then closed and the low-duty valve open, and that under high-duty conditions, the high-duty valve being open and the low-duty valve closed, the high-duty flow is measured proportionally by the high-duty proportional metering device a^{10} , a^{11} and a^{12} .

Other forms of metering devices than those indicated may be employed to suit different conditions of use and may be arranged as may be most convenient. The construction of the valves and of the mechanical devices by which the movement of the one is effected from the other may also be changed to suit different conditions. The invention, therefore, is not restricted to the particular construction and arrangement of parts shown and described herein.

I claim as my invention:—

1. The combination with a meter casing having a transverse wall with an aperture therethrough, of a valve to close said aperture, said valve comprising a main part and

a central part movable with respect to the main part and in the same direction therewith and an independent valve to which one of the parts of said first named valve is 5 operatively connected, said relative movement between said parts permitting said independent valve to be moved upon the movement of one of said parts and prior to the movement of the other of said parts.

10 2. The combination with a meter casing having a transverse wall with an aperture therethrough, of a valve to close said aperture, said valve comprising a main part, a central part movable with respect to the 15 main part and in the same direction therewith, and a flexible diaphragm interposed between the valve seat and the valve and carried by the valve and an independent valve to which one of the parts of said first 20 named valve is operatively connected, said relative movement between said parts permitting said independent valve to be moved upon the movement of one of said parts and prior to the movement of the other of said 25 parts.

3. The combination with a meter casing having a transverse wall with an aperture therethrough, of a valve to close said aperture, said valve comprising a main part, a central part movable with respect to the main part and in the same direction therewith, a flexible diaphragm secured to the main part and covering the central part and an independent valve to which one of the 35 parts of said first named valve is operatively connected, said relative movement between said parts permitting said independent valve to be moved upon the movement of one of said parts and prior to the movement 40 of the other of said parts.

4. The combination with a meter casing having a transverse wall with an aperture therethrough, of a cam arm, a valve to close said aperture, said valve comprising a main 45 part and a central part movable with respect to the main part and in the same direction therewith, a lever pivotally connected to the main part and to the central part, a connection between said lever and the cam arm and an independent valve to 50 which one of the parts of said first named

valve is operatively connected, said relative movement between said parts permitting said independent valve to be moved upon the movement of one of said parts and 55 prior to the movement of the other of said parts.

5. The combination with a meter casing having a transverse wall with an aperture therethrough, of a cam arm, a valve to close 60 said aperture, said valve comprising a main part and a central part movable with respect to the main part and in the same direction therewith, toggle levers pivoted upon the main part and connected to the 65 central part, a yoke connecting the toggle levers with the cam arm and an independent valve to which one of the parts of said first named valve is operatively connected, said relative movement between said parts permitting 70 said independent valve to be moved upon the movement of one of said parts and prior to the movement of the other of said parts.

6. The combination with a meter casing 75 having a transverse wall with an aperture therethrough, of a cam arm, a shaft to which the cam arm is fixed, an operating arm fixed to said shaft, an adjusting arm mounted loosely on said shaft, adjusting means to 80 adjust the relative position of the two last named arms, a valve connecting to said adjusting arm and an independent valve operatively connected to said operating arm.

7. The combination with a meter casing 85 having a transverse wall with an aperture therethrough, of a cam arm, a shaft to which the cam arm is fixed, an operating arm fixed to said shaft, an adjusting arm mounted loosely on said shaft, a cam arm engaging a 90 slot in the loosely mounted arm, clamping means to clamp the loosely mounted arm in adjusted position with respect to the cam arm, a valve connected to the rigid arm and an independent valve operatively connected 95 to said operating arm.
